A. H. FLEMING.

BELT.

APPLICATION FILED OCT. 30, 1916.

1,225,947.

Patented May 15, 1917.

FIG. 1.

UNITED STATES PATENT OFFICE.

ALLISON HOWARD FLEMING, OF FAIRMONT, WEST VIRGINIA.

BELT.

1,225,947.

Specification of Letters Patent.

Patented May 15, 1917.

Application filed October 30, 1916. Serial No. 128,451.

To all whom it may concern:

Be it known that I, ALLISON H. FLEMING, a citizen of the United States of America, residing at Fairmont, in the county of Marion, State of West Virginia, have invented certain Improvements in Belts, of which the following is a description, reference being had to the accompanying drawings, forming a part hereof.

10 The object of the invention is to provide a trousers supporting belt, having means surmounting and bearing upon the hips of the wearer in such a manner and under such conditions as to maintain the belt in a plane 15 above the hips, so that the lateral or compressive bearing of the belt shall impose upon the relatively soft fleshy portions of the waist of the wearer, said means being of such a construction as to conform sufficiently to the curvature of the body to insure ease and permanence of location, and being provided with devices for engaging the trousers waist band to hold the latter securely in a plane with the upper edge 25 above the belt, to thereby conceal the same.

Further objects and advantages of the invention will appear in the following description of a preferred embodiment thereof, it being understood that changes in the form, 30 proportion and minor details may be resorted to within the scope of the appended claims without departing from the spirit of the invention.

In the drawings,

35 Figure 1 is a view showing a belt illustrating one embodiment of the invention applied in the operative position.

Fig. 2 is a detail view of one of the hip-surmouinting elements and the adjacent 40 portion of the belt.

Fig. 3 is a detail vertical section of the same.

Fig. 4 is a detail perspective view of the plate and trousers engaging members of the 45 hip-surmouinting element with the parts detached.

The invention embodies essentially a belt 10, provided at intervals with hip-surmouinting elements 11, designed to rest upon the 50 hips of the wearer in such a way as to support the device with the belt surrounding the relatively softer portions of the waist of the wearer, whereby the parts may be held in the proper position without tightening the belt to such an extent as to cause 55 inconvenience, and preferably the hip-surmouinting elements are slidably mounted upon the belt so as to provide for adjustment to suit different girths of wearers. These hip-surmouinting elements are stiffened and extend upwardly from the plane of the belt, and are provided with trousers engaging devices which in the construction illustrated consists of clamps 12, of a conventional or preferred type at the upper 60 extremities of arm 13. Preferably the hip-surmouinting element has a body portion consisting of a plate 14, shown in detail in Fig. 4, which is doubled upon itself and is provided with an inclosing sheath 15, held 65 in place by marginal stitching. The plate with its sheath should also be provided with openings registering with corresponding openings in the arms of the trousers engaging members and eyelets 17 engaging the 70 openings to secure the parts in their several relative positions as shown in Figs. 1 and 2, the lowermost eyelet serving to define the 75 guide-way through the hip-surmouinting element for the reception of the belt.

The hip-surmouinting elements are preferably made of such a width as to insure a firm, substantial and easy bearing upon the hips of the wearer, but in order to prevent intermediate portions of the trousers band from sagging supplemental supporting elements 18, having a construction similar to that just described with reference to the hip-surmouinting element, may be slidably mounted upon the belt to provide for adjustment for the same reason as described with reference to the hip-surmouinting elements. Also said supplemental elements are provided as shown with trousers engaging devices.

After adjusting the belt around the waist, at the proper comfortable tensions, and arranging the hip-surmouinting elements directly over the bearing at their lower edges on the hip, the supplemental supports should be placed as desired relatively to the hip-surmouinting elements, after which the clamps may be engaged with the upper edge of the trousers band, the belt and supports being concealed thereby and the upper edge of the band being held in the desired plane.

After this adjustment and engagement with the trousers, the belt may remain in place on the clothing, it being necessary only to loosen the belt, by detaching its extremities to permit the removal of the clothing, and when the latter is replaced the parts

accurately assume their proper positions. In other words, the belt may be permitted to remain attached to the trousers, as the latter are successively removed and replaced, and 5 is always in position for use,—becoming effective simply by tightening the belt at the buckle 19.

It will be observed that the rounded lower bearing edge formed by the doubling of the 10 stiffening plate of the hip-surmounting elements avoids any cutting or chafing action, especially as said plate is covered by the sheath of canvas or other suitable fabric, and the only exposed metal parts are the clamps 15 and their flat supporting arms, which parts are preferably highly polished to avoid abrasion of the garments.

What is claimed is:

1. A trousers-supporting belt having flat 20 stiffened hip-surmounting elements slidably mounted upon and adapted to maintain the belt in a plane above the hips of the wearer, each of said elements consisting of a folded member forming a belt-receiving guide, and 45 an upwardly extending trousers-engaging device carried by said member and secured between the folds thereof to define the width of the belt-receiving guide.

2. A trousers-supporting belt having flat

stiffened hip-surmounting elements slidably 30 mounted upon and adapted to maintain the belt in a plane above the hips of the wearer, each of said elements consisting of a plate provided with an inclosing fabric sheath, doubled upon itself to form a lower rounded 35 bearing edge, and an upwardly extending trousers-engaging device carried by said member and secured at its lower end between and spacing the folds of said member, and terminating short of the bottom of the same 40 to define a belt-receiving guide.

3. A trousers-supporting belt having flat stiffened hip-surmounting elements adapted to maintain the belt in a plane above the hips of the wearer, each of said elements consisting of a folded and stiffened member, a trousers engaging device having its arm located between the parts of said folded member, and fastening means extending through the parts of the folded member and the arm, the 50 end of the latter defining a belt receiving guide between parts of the folded member.

This specification signed and witnessed this 24th day of October A. D. 1916.

ALLISON HOWARD FLEMING.
